BOTTLE CASE

Hugo C. Haffner, Brooklyn, N. Y.

Application June 19, 1951, Serial No. 232,379

2 Claims. (Cl. 217—22)

1

This invention relates to shipping cases for bottles of beer and other beverages.

An object of the invention is to provide an improved shipping case in which the filler will remain in properly arranged and locked relation until positively removed therefrom.

A further object of the invention is to provide an improved shipping case in which the filler may be readily assembled, reversed or replaced, and when properly located in the case, will not become displaced during the handling or shipment of the case.

Other objects of the invention as well as the advantages and novel features of construction thereof, will become apparent after a perusal of the following description when read in connection with the accompanying drawings, in which Fig. 1 is a top plan view, partly in section, of a beer case made in accordance with the invention; Fig. 2 is a vertical sectional view taken along the line 2—2 of Fig. 1; Fig. 3 is a vertical sectional view taken along the line 3—3 of Fig. 1; Fig. 4 is a fragmentary, sectional view similar to that of Fig. 2 showing a modified form of the invention; Fig. 5 is a top plan view, partly in section, of another embodiment of the invention, and Fig. 6 is a detail sectional view of the box shown in Fig. 5.

In the drawings, the reference numeral 10 designates the two side walls of the case and the reference numeral 11, the end walls thereof. The walls 10 and 11 are made of substantially rigid material such as heavy cardboard, wood or any other suitable material and the end walls 11 may be made of thicker stock than the side walls 10. The box may be provided with any suitable bottom such as the slatted bottom illustrated and composed of spaced strips 20 suitably secured to the end walls 11. The end portions of the case are strengthened as usual, by enveloping metal bands 12 seated in grooves provided in the ends of the side walls 10 and the strips 20. It will thus be seen that the box or case is formed of the parts 10, 11, 12 and 20 to provide a rigid, unitary structure.

For dividing the container into compartments, there are provided two longitudinally extending strips 14 and three transversely arranged strips 13. The strips 13 and 14 are suitably interlocked at their intersections and are made of cardboard or any other suitable material. Preferably a cardboard material about .065 of an inch thick and treated to render it waterproof, is best suited for the purposes of the invention. While the strips 13 and 14 have substantial rigidity, the

2

longitudinal strips are of sufficient flexibility in a transverse direction to enable the ends thereof to be bent in the manner indicated by the dotted line portions thereof in Fig. 1 of the drawings and have sufficient inherent resiliency to enable such end portions to move to their normal full line positions when released. The depth of the strips 13 and 14 are the same and such that they extend upwardly from the bottom of the casing to a point spaced below the hand holes of the casing (note Figs. 2 and 3).

The transverse strips 13 have a length greater than the inside width of the case and the ends thereof are located in vertical grooves or slots 15 provided on the side walls 10 and extending throughout the entire depth or width of such side walls. The longitudinal strips 14 have a length slightly less than the inside length of the case. Provided at the ends of each longitudinal strip 14 are centrally located projections 17 formed to be readily received in the transverse grooves or slots 16 provided on the end walls 11.

In assembling the filler composed of the interlocked strips 13 and 14, the operator grasps in each hand the two adjacent ends of the longitudinal strips 14 bending or flexing them toward each other in the manner indicated in dotted outline in Fig. 1 of the drawings. With the ends of strips 14 so grasped, the ends of the transverse strips 13 are inserted in the slots 15 in the side walls 10 of the box and then the filler is pushed down into the box until the bottom edges of the filler engage the slat pieces 20. The ends of the longitudinal strips 14 are then released, to permit the inherent resiliency of the material thereof to straighten out the ends of such strips, the projections 17 thereof during the return of such ends entering into the slots 16 in the end walls of the case. When it is desired to remove or reverse the filler so inserted, the same method is followed. It will thus be seen that the insertion or removal of the filler can be accomplished with ease. When the filler is in place in the case, the end edges of the transverse strips 13 are locked against displacement lengthwise of the case, while the interengagement of the projections 17 with the grooves 16 will lock the strips 14 and consequently the strips 13 interlocked therewith, against vertical displacement with respect to the walls of the case. Thus, the filler will stay in position and cannot be lost in handling as during inspection, removal of the bottles for purposes of washing or stacking on shelves. The filler is effectively locked against any possible removal when empty or full bottles are contained

in the case because in this event, the ends of the longitudinal strips 14 will be prevented by the bottles from being displaced sideways sufficiently to enable the projections 17 to unlatch from the grooves 16.

While the longitudinal strips 14 are shown as having one projection or lug 17 in a centrally located position on each end thereof, it will be understood that more than one such projection may be provided on each end of a longitudinal strip 14. Thus, as shown in Fig. 4 of the drawings, each end of the longitudinal strip may be provided with a plurality of projections 17 arranged to interengage with a plurality of grooves 16 provided in the end walls 11 of the case. When a plurality of such projections are so provided on the longitudinal strip they should preferably be arranged symmetrically thereon, as illustrated in Fig. 4 so that the filler can be reversed in the case.

Instead of using interlocking projections and grooves such as illustrated in Figs. 1-4 of the drawings, it is within the contemplation of the invention to provide projections on the end walls 11 for interlocking with one or more notches or recesses provided in the ends of the longitudinally extending strips 14. In this embodiment of the invention, it is preferred that such projections be composed of lugs provided with shanks that are driven into or otherwise secured to the material of the end walls 11 of the case at the exact places desired. As is shown in Figs. 5 and 6 of the drawings, such lugs 18 are preferably of plate-like form so that they will readily enter the recesses 19 in the longitudinal strips 14, when the ends thereof are released after insertion of the filler within the case in the manner previously described. Preferably also, the side edges of such lugs 18 are inclined so that the bottles can be readily inserted in the end compartment of the case by the packing machine (note the relation of the bottles to the lugs 18 as indicated by the dotted circles in Fig. 5 of the drawings).

I claim:

1. A bottle case having side and end walls and a bottom, the end walls of said case being substantially rigid, a readily insertable and removable filler in said case composed of a plurality of flexible transverse and longitudinally extending strips connected together as a unit, a plurality of the longitudinal strips in said filler unit having a length less than the inside length of said case, and being provided on their ends with longitudinally projecting members having a depth substantially less than the depth of said strips and located between the top and bottom edges thereof, said end walls being provided with

45

50

55

horizontal grooves between the top and bottom edges thereof receiving said projecting members in a horizontal direction and coacting with such members to prevent movement of said filler unit in a vertical direction, the ends of said longitudinal strips being capable of being readily flexed out of normal position in a horizontal direction to enable the filler unit to be inserted or received and having sufficient inherent resiliency to cause said projecting members to interlock with such horizontal grooves when released after insertion of the filler into the case.

2. A bottle case having side and end walls and a bottom, the end walls of said case being substantially rigid, a readily insertable and removable filler in said case composed of a plurality of flexible transverse and longitudinally extending strips connected together as a unit, a plurality of the longitudinal strips in said filler unit having a length less than the inside length of said case and being provided on their ends with longitudinally projecting members having a depth substantially less than the depth of said strips and located between the top and bottom edges thereof, the transverse strips in said filler having a length greater than the inside width of said case, said side walls being provided with vertical grooves having open ends at the tops of said side walls, the ends of said transverse strips being slidable in the open ends of such grooves to be removably retained in such grooves, said end walls being provided with horizontal grooves between the top and bottom edges thereof receiving said projecting members in a horizontal direction and coacting with such members to prevent movement of said filler unit in a vertical direction, the ends of said longitudinal strips being capable of being readily flexed out of normal position in a horizontal direction to enable the filler unit to be inserted or received and having sufficient inherent resiliency to cause said projecting members to interlock with such horizontal grooves when released after insertion of the filler into the case.

HUGO C. HAFFNER.
